Application March 20, 1947, Serial No. 735,965

5 Claims. (Cl. 40—128)

1

This invention relates to signs, and has particular reference to a sign construction in which character displaying plates may be locked or clamped in place by means of a novel supporting frame arrangement.

The primary object of the invention is to provide a sign of the character described wherein said plates may be placed in proper position in the sign with unusual ease and facility, and locked against removal from the sign, the support from which the sign depends being adapted by means of an unusual construction to serve as the locking member.

Another important object of the invention is to provide a sign of the type described which is so constructed as to resist with unusual effectiveness any attempts at malicious mischief in connection therewith, such as removal of the character plates, or the like.

A further important object of the invention is to provide a novel type of sign that is constructed unusually inexpensively, and yet is of exceptional durability and strength.

Still another object of the invention is to provide a sign in which the character plates are automatically locked in place by the act of hanging the sign.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings:

Figure 1 is a front elevational view of a sign constructed in accordance with the invention, the dotted lines indicating the position taken by the supporting members whereby the sign is hung, when it is desired to change or insert new character plates, before hanging the sign.

Figure 2 is a view taken substantially on line 2—2 of Figure 1.

Figure 3 is a fragmentary detail perspective view, showing the center portion of the sign, a portion of a character plate being shown in locked position.

Referring to the drawings in detail, the reference character 5 designates a pair of longitudinal outer frame members which are spaced apart in parallel relation, and which are preferably formed from lengths of heavy wire material. The ends 55

2

ends of parallel transverse outer frame members 6, thereby forming a rectangular outer frame.

A rectangular inner frame is also provided, and this is formed with parallel longitudinal inner frame members 7, that are also parallel to the members 5. Disposed parallel to, and a short distance above, the lower of the longitudinal inner frame members 7 is a lower plate guard 8, which is also preferably formed from a length of stiff wire material.

Disposed parallel to, and spaced a short distance below, the upper of the members 7, is an upper plate guard 9. The guards 8 and 9, as will be explained in detail hereinafter, prevent removal of the character plates from the front of the sign, the plates being locked behind these guards.

Throughout the length of the lower plate guard 8, at spaced intervals, are connected thereto as by welding or the like, the ends of lower transverse brace wires 10. The other ends of the brace wires 10 are similarly joined to the lower of the longitudinal outer frame members 5. These are also rigidly joined, intermediate their ends, to the lower of the longitudinal inner frame members 7. Thus, the lower plate guard 8 is fixedly mounted in position in spaced relation from, and is rigidly joined to, the lower of the members 7. By means of the brace wires 10 whereby this is achieved, the lower of the members 7 is similarly mounted and rigidly connected to the lower of the outer frame members 5.

A similar arrangement is effected longitudinally of the upper portion of the sign. Upper transverse brace wires 11 are rigidly connected at spaced intervals, at one end, to the upper of the longitudinal outer frame members 5. Intermediate their ends they are rigidly connected to the upper of the longitudinal inner frame members 7. Their other ends are rigidly joined to the upper plate guard 9.

The ends of the longitudinal inner frame member 7 are fixedly connected to parallel transverse inner frame members 12 and it is thus seen that a rectangular inner frame is provided within the larger correspondingly formed outer frame. Brace wires 13 connect the transverse outer frame members 6 and the inner frame members 12.

The ends of the plate guards 8 and 9 are also fixedly joined by transverse members 14, and this completes the basic outer and inner frame structures, rigidly joined as described to provide a supporting frame having a rectangular central opening or window behind which the character plates

are placed for display purposes. Longitudinal rear supporting rods 15 are provided, that are arranged parallel to, and immediately rearward of, the plate guards 8 and 9. These are of a length corresponding to the length of the plate guards 8 and 9, and are spaced therefrom only enough to permit the entry therebetween of a character plate, as clearly shown in Figures 2 and 3. Intermediate their ends the rods 15 are rigidly connected by parallel transverse brace rods 16. The lower ends of the brace rods 16 extend below the connection thereto to the lower of the longitudinal rods 15, and are forwardly curved as clearly shown in Figure 3, and are fixedly connected at their extremities to a longitudinal bottom supporting rod 18. As clearly shown in Figures 2 and 3, the bottom supporting rod 18 constitutes a support for the bottom edges of the character plates, and is positioned so as to engage along its length the lower of the longitudinal inner frame members 7.

For the purpose of strengthening the connection between the rear supporting rods 15, I provide additionally a plurality of transverse brace wires 19 that are fixedly connected at their ends to the said rods 15.

Connecting the ends of the rear supporting rods 15, and also fixedly joined to the ends of the bottom supporting rod 18 and to the members 7, are rod supports 20, the upper ends of which are bent to provide rearwardly directed eyes 21.

Engaged by the eyes 21 are eyes 22 formed on the ends of angular supporting members 23, that are extended toward each other, and bent upwardly intermediate their ends to provide longitudinally engaging arms 24. The upper ends of the arms 24 are formed with hooks 25 which, when the arms are brought together into the full line position shown in Figure 1, lap oppositely, to provide a single opening.

For the purpose of reinforcing each of the supporting members 23, I prefer to employ diagonal braces 26, the ends of which are rigidly connected to the respective members 23 adjacent the ends of said members.

Each member 23 is provided with a yoke member 27. This is fixedly connected to the member 23 intermediate its ends, and has its arms downwardly extended from said point of connection, so as to straddle the upper of the rear supporting rods 15, the upper of the longitudinal frame members 7, and the upper plate guard 9. Thus, when the members 23 are lowered into position for supporting the sign, as shown by the full lines of Figure 1, the members 23 are held against movement, substantially, by the yoke members 27.

The character plates embodied in the invention have been designated by the reference character 28, and are preferably in the form of rectangular flat glass plates, each having a distinctive character thereon. To insert the plates, the supporting members 23 are positioned as shown in the dotted lines in Figure 1. By reference to Figure 2, in which it is seen that these members engage the top edges of the character plates 28, it is seen that this action will provide a suitable opening through which the plates 28 may be inserted or removed from the sign. After the plates have been inserted as desired, the members 23 are swung downwardly and toward each other, until they are in the full line position shown in Figure 1. A lag bolt 29, or the like, is then passed through the opening formed by the overlapping hooks 25, the bolt 29 being screwed into a supporting surface S or the like.

Preferably, a threaded washer 30 is threaded onto the bolt 29 rearwardly of the hooks 25, and serves as a spacing washer, effectively preventing the hooks from sliding rearwardly on the bolt.

5 To effectively secure the sign to the bolt 29, there is preferably also provided a nut 31 which may be specially formed so as to receive only a correspondingly formed wrench.

From the description provided hereinbefore, it is seen that I have provided a sign of novel design, wherein a supporting frame retains against removal in a rearward, forward, or lower direction, the character plates insertable in the window provided in the supporting frame for display purposes. The plates 28 are removable only from the top, in an upward direction. An important characteristic of the invention, in this connection, is the fact that the supports from which the sign depends are so formed and arranged as to close the top of the window, when the sign is hung. When placed in this position, the supporting members 23 engage the top edges of all the character plates, and at the same time provide a single opening, by means of thelapping hooks 25, through which a bolt may be passed. As a result, the character plates, though openly displayed and otherwise unprotected, are locked against removal automatically, by the act of mounting the sign on a supporting surface.

10 20 25 30 Obviously, deviations can be made from the exact embodiment of the invention which has been illustrated and described herein, without departure from the spirit of the invention.

What is claimed is:

35 1. A sign comprising a supporting frame formed with a display opening adapted to receive character plates, the opening being open at its top for entry and removal of the character plates and closed against removal of the character

40 45 50 plates from the front, bottom, and rear, supporting members pivoted at one end to the supporting frame at the ends of the display opening for swinging movement into a position in which they are aligned longitudinally and cooperate to close the open top of the opening, arms on the respective supporting members engageable longitudinally when the supporting members are so swung, and hooks on the arms overlapping when the arms are so engaged, to provide a single aperture for receiving a supporting means.

2. A sign comprising a supporting frame formed with a display opening adapted to receive character plates, the opening being open at its top for entry and removal of the character plates and being closed against removal of the character plates from the front, bottom, and rear, and supporting members movably connected to the supporting frame adjacent the display opening, said supporting members being movable into a position in which they are longitudinally aligned above said opening and close the open top of the opening, the supporting members being respectively provided with support-receiving apertures positioned to register when the supporting members are in said position.

3. A sign comprising a supporting frame having a display opening, the display opening having a slot for insertion and removal of, character plates, supporting members each movably connected at one end to the supporting frame, the supporting members being movable into position in which they are aligned longitudinally and cooperate to close the slot, the supporting members being formed at their other ends for interengagement when the supporting members are in said

positions, and means for locking the latter ends to a sign support.

4. In a sign a frame having a display opening, the opening being formed with a slot at its top for receiving character plates, a combined sign-supporting and closure means for said slot, comprising a pair of elongated rod members respectively swingably connected at their outer ends to the frame at opposite ends of the slot, said members being swingable toward each other into a position in which they are longitudinally aligned to close the slot, the other ends of the members being formed with hooks, said hooks overlapping when the members are swung toward each other, to provide an opening for receiving a supporting means.

5. In a sign a frame having a slot, a pair of supporting members therefor respectively pivotally connected at their outer ends to the frame for swinging movement into a position in which

they are substantially aligned longitudinally to cooperate to close the slot, and eyes on the inner ends of the members registering in said position of the members for locking of the members against movement relative to each other and to the frame, on passage of a supporting pin through the registered eyes.
